(57) **CLAIM**

The ornamental design for material layering device, as shown and described.

DESCRIPTION

FIG. 1 is a perspective view of a material layering device in an assembled state employing an ornamental design in accordance with the present invention;

FIG. 2 illustrates a side view thereof;

FIG. 3 is another side view thereof, identical to FIG. 2.

FIG. 4 is another side view thereof, identical to FIGS. 2 and 3.

FIG. 5 is another side view thereof, identical to FIGS. 2, 3, and 4.

FIG. 6 illustrates a top view thereof;

FIG. 7 illustrates a bottom view thereof;

FIG. 8 is a first perspective view of the material layering device of FIG. 1 in a disassembled state illustrating a base plate and a top plate separated from one another; and,

FIG. 9 is a second perspective view of the material layering device of FIG. 1 in a disassembled state illustrating a base plate and a top plate separated from one another.
